CLAIM

The ornamental design for a child safety cabinet lock as shown and described.

DESCRIPTION

FIG. 1 is a front, left, and top perspective view of a child safety cabinet lock, showing our new design;

FIG. 2 is a rear, right, and bottom perspective view thereof;

FIG. 3 is a front view thereof;

FIG. 4 is a rear view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front and top perspective view of the child safety cabinet lock of FIG. 1 in a use state;

FIG. 10 is another front and top perspective view of the child safety cabinet lock of FIG. 1 in a use state;

FIG. 11 is an enlarged view of an encircled area labeled “11” in FIG. 9; and,

FIG. 12 is an enlarged view of an encircled area labeled “12” in FIG. 10.

The broken lines depict portions of the child safety cabinet lock that form no part of the claimed design.

1 Claim, 12 Drawing Sheets
